(57) **CLAIM**

The ornamental design for notebook computer, as shown and described.

DESCRIPTION

FIG. 1 is a perspective view of the notebook computer in a configuration wherein both of a main display and a sub-display are unfolded;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the notebook computer in a configuration wherein the main display is unfolded and the sub-display is folded;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIG. 15 is a perspective view of the notebook computer in a configuration wherein both of the main display and the sub-display are folded.

The broken lines, showing lettering and icons on the sub-display of the notebook computer in FIG. 15, represent environment that forms no part of the claimed design. All

(Continued)

other broken lines in FIGS. 1-15 represent unclaimed portions of the notebook computer and form no part of the claimed design.

1 Claim, 15 Drawing Sheets
